UNITED STATES PATENT OFFICE.

ANTON ZEMAN, OF CHICAGO, ILLINOIS, ASSIGNOR TO JOSEPH SALTZMAN, OF CHICAGO, ILLINOIS.

PRESSING MACHINE.

Application filed January 16, 1924. Serial No. 686,479.

My invention has reference more particularly to pressing machines of the type used in tailor shops and other similar establishments, for pressing clothes.

5 The principal objects of my invention are to provide an improved pressing machine; to compound the leverage for the pressing element whereby a very high pressure is effected without excessive exertion on the part 10 of the operator; to facilitate the return of the pressing element to the inoperative position; to provide means for automatically governing or regulating the temperature of the pressing element; to arrange the counterbalancing springs so that they effectively 15 return the parts to the former position; to effect an inclination of the carriage which facilitates the return of the presser element to the normal retracted position after each 20 operation; and in general, to simplify and increase the efficiency of pressing machines of this type.

On the drawings:

Fig. 1 is a side view of a pressing machine 25 embodying my improvements, with parts broken away to disclose details of the construction;

Fig. 2 a front view of the pressing machine;

30 Fig. 3 a fragmentary sectional view on the line 3—3 of Fig. 1;

Fig. 4 a side view showing the pressing element in the retracted position and with 35 rear portions of the frame broken away to disclose details of the presser operating mechanism;

Fig. 5 a fragmentary rear view of the 40 pressing machine; and

Fig. 6 a detail sectional view on the line 45 6—6 of Fig. 1.

Referring to the drawings, the reference numeral 1 indicates the base of the machine which is preferably formed integral with the pair of side standards 2 which are connected by a top plate 3 and a transverse brace 4. A shaft or upright standard 5 is mounted in a substantially upright position at the rear of the frame between the side standards 2 and projects upwardly through

a notch 6 in the rear of the top 3, which latter is preferably provided with a semi-circular guard 7 extending around the front and sides of the shaft. A pair of bearing lugs 8 depend from the top 3, and are provided with apertures in alignment with bearing apertures in lugs 9 of the side frames to receive the shaft 10 which forms a pivot pin for a link 11 which has the upper end interposed between the bearing lugs 8.

A pair of links 12 are also pivoted on the shaft 10 at the outer sides respectively of the bearing lugs 8 and extend rearwardly upon opposite sides of the upright shaft 5. These lugs have their rear ends pivoted on laterally projecting studs 13 of the collar 14, 65 which is secured to the shaft 5 by the set screw 15.

A lever 16 having a substantially T-shaped rear end, is interposed between the side frames 2 and is provided at its forward 70 end beyond the frames 2 with a treadle 17. This lever has the upper arm of the T-shaped rear end extending at an obtuse angle and divided to receive the lower end of the link 11 to which it is pivoted by a pivot pin 75 18, and the lower arm of the T-shaped rear end of the lever 16 is extended at an obtuse angle and likewise divided to receive the upper end of the link 19 which is pivoted there- 80 to by the pin 20.

A socket 21 is secured on the lower end of the shaft 5 by the pin 22, or in any other suitable manner, and has a pair of bearing lugs 23 extending forwardly therefrom and embracing the lower end of the link 19 to 85 which these lugs are pivotally connected by the pivot shaft 24.

The rear end of the lever 16 is connected at a point between the pivots 18 and 20 to a collar 25 which is held on the shaft 5 90 by the set screw 26, said connection comprising the links 27, which are arranged respectively at the opposite sides of the shaft 5 and have their forward ends engaged on the pivot pin 28 of the lever 16, and have their rear ends engaged on pivot studs 29 which project laterally from the collar 25.

The collar 14 and socket member 21 are

formed at each side with laterally projecting lugs 30 and 31 respectively which terminate close to the opposed parallel flanges 32 of the side frames 2 to prevent lateral displacement of the shaft 5.

5 A heavy spring 60 has its lower end connected to the lever 16 a short distance in front of the pivot pin 28 and has its upper end connected to a hook 61 on the under side 10 of the top 3 so as to hold the lever 16 in the elevated position as shown in Fig. 4.

From the foregoing it will be observed that the shaft 5 which carries the presser head, is hung from the frame of the machine 15 by the links 11 and 19 and the T-end of the lever 16 in substantially the same manner as shown in the structure of the patent to Schrom No. 1,004,697. In the structure of said patent, however, the lower end of 20 the upright shaft which carries the presser head is stayed by a pair of links which are pivoted to the frame of the machine and to the socket at the lower end of said shaft, and the latter has practically only an up 25 and down movement.

In my construction, however, the socket 21 at the lower end of the shaft 5, is connected to the lower part of the side frames 2 by toggle links 33 and 34, which are pivot- 30 ed together at their inner ends on the pivot 35, and the outer ends of the links 33 are pivoted on the shaft 24 of the socket 21, while the outer end of the toggle link 34 is pivoted on the shaft 36, which has the op- 35 posite ends engaged in corresponding bearings 37 of the two side frames 2 as indicated particularly in Fig. 3.

A pair of links 38 which are arranged respectively at opposite sides of the lever 16 40 and toggle link 34, are pivoted at their upper ends to the lever 16 by the pin 39 and have their lower ends pivotally engaged on the shaft 35 so that when the lever 16 is in the elevated position shown in Fig. 4, 45 the toggle joint formed by the toggle links 33 and 34 is broken upwardly, and when 33 and 34 are depressed as shown in Fig. 1, the lever 16 is depressed into substantially an aligning position.

50 Thus the distance between the stationary shaft 36 and the shaft 24 is shortened when the lever 16 is elevated, and the lower end of the upright shaft 5 is accordingly moved forwardly to tilt and raises the shaft 5 rear- 55 wardly at a slight angle to the vertical as shown in Fig. 4, with the result that the carriage for the presser head is tilted slightly. This not only serves to increase the elevation of the pressing member above the 60 pressing buck to facilitate insertion and removal of the clothes and increase the capacity but also tends to slide the pressing element rearwardly by gravity to the retracted 65 position and facilitates operation of the pressing device. That is, the shaft 5 is

oscillated forwardly and rearwardly on its horizontal axis near its lower end and is raised when swung rearwardly by the raising of the treadle 17 when released, and is swung forwardly and lowered when the 70 treadle is depressed to exert great pressure upon the materials being pressed. On the other hand, this arrangement affords increased clearance for bringing the pressing element over the article which is to be 75 pressed on the pressing buck, and also serves to exert a powerful leverage on the lower end of the shaft 5, as the links 11 and 19 and the end of the lever 16 are straightened out, and imposes an exceedingly high pressure of the pressing element against the article on the pressing buck, and accomplishes this high pressure without great effort on the part of the operator.

80 The shafts 24 and 36 are preferably ex- 85 tended sufficiently to accommodate a pair of springs 59 which connect the corresponding ends of these shafts and serve to facilitate the elevation and rearward movement of the pressing mechanism and breaking of 90 the toggle joint connection of the links 33 and 34 and bend this articulated joint up- 95 wardly as seen in Fig. 4 by drawing 24 toward 36, and thus 21 and 5 forwardly. The opposite action takes place when the treadle 17 is depressed.

The carriage which has been hereinbefore referred to, is indicated at 40 and consists of an elongated head with an opening extending therethrough from end to end to 100 loosely receive the bar 41 which is engaged between the upper and lower anti-friction rollers 42, which are journaled in the head and permit easy sliding movement of the bar 41 through the head. This head is 105 formed with a pair of vertically spaced collar portions 43 and 44 which embrace the upper end of the shaft 5 and have a collar or sleeve 45 interposed therebetween and secured on the shaft 5 by the pin 46 110 or in any other convenient manner.

In cases where this machine is provided with an ordinary iron which it is desired to move along the upper surface of the pressing buck, the collars 43 and 44 are free to 115 turn on the shaft 5. In the present structure, however, a pressing element 47 is employed, which merely clamps down against the top of the buck 48 and as sidewise lateral movement or oscillation is not desired, the 120 collars 43 and 44 are locked onto the shaft 5 by the pins 49 or in any other convenient manner.

Secured to the forward end of the bar 41 125 is a cross head 50 which supports the pressing element 47. The latter comprises an elongated shell having a flat bottom corresponding in form to the top surface of the pressing table or buck 48 and adjustably 130 connected at spaced points by means of the

screws 51 to the ends of the cross head 50. A handle 52 is attached to the front of the pressing element 47 for convenient manipulation of the latter.

- 5 Extending lengthwise within the heating element 47 is a gas burner 53, which has an inlet pipe 54 connected thereto at the center, and this inlet pipe is connected through the manually operable valve 55 by the hose 56
 10 to a gas supply pipe 57, the hose being sufficiently loose and suitably caught up as indicated at 58 so that the pressing element may be readily raised and lowered and moved backwardly and forwardly on the
 15 pressing machine.

A similar gas burner 62 is mounted under the top plate of the pressing table 48 and has the inlet pipe 63 at the center connected through the manually operable valve 64 and

- 20 tubing 65 to the main supply pipe 57. A valve 66 which is automatically operable by a thermostat, is connected to the supply pipe 57 so as to simultaneously control the admission of gas to both of the heating elements 53 and 62, the device of this automatic valve not being shown, as such valves are already on the market, and any suitable thermostatically operated valve may be employed. A thermostatic element 67 is
 25 mounted by means of brackets 68 under the top plate of the pressing table 48 and connected by means of the tubing 69 with the automatic valve 66 in the usual manner for controlling the operation thereof. A handle 70 on this valve serves to set the latter at any desired temperature which is automatically maintained by the valve through the medium of the thermostatic element 67.

With this construction, when the handle

- 30 70 is set at the temperature desired for pressing, the flow of gas through the tubes 56 and 65 to the burners 53 and 62 is automatically regulated so as to maintain the required temperature. A manually operable valve 71 is provided in the supply pipe 57 for entirely shutting off the supply of gas.

For limiting the movement of the lever 16, the cross brace 4 of the main frame is
 35 provided with a suitable inset bumper 72, and the base of the machine with a similar inset bumper 73, which project sufficiently and are composed of suitable material to cushion the impact of the lever at the extremities of its movement. The cross brace 4 is also formed with a transverse rib 75 with which a latch 76 on the treadle operates for holding the treadle in the depressed position. This latch 76 is pivoted
 40 at 77 and has a laterally offset extension 87 which projects below the treadle and is connected to a spring 78 which serves to throw the latch 76 into engagement with the rib 75. An operating lever 79 is pivoted at
 45 80 near the lower extremity of the extension

87 and has an upwardly extending arm 81 connected by the spring 82 with the upper end of the extension 87, and this operating member 79 extends forwardly and has a stem 83 projecting up through the treadle 17
 50 and provided with a button or small plate 84 at the upper end, which may be depressed to release the latch 76 from the rib 75.

An extension 85 is hinged at each side of the top of the pressing machine and held in
 55 the elevated position by a brace 86 extending down to the base of the machine.

While I have shown and described my invention in a preferred form, I am aware that various changes and modifications may
 60 be made without departing from the principles of my invention, the scope of which is to be determined by the appended claims.

I claim as my invention:

1. In a pressing machine, the combination
 65 of a main frame having a pressing table
 thereon, an upright shaft mounted to swing
 on the frame and having a pressing element
 thereon to one side of the shaft for pressing
 articles on the pressing table, a treadle and
 70 mechanism operated thereby for raising and
 lowering the shaft, and means operated by
 the treadle to swing the shaft and thereby
 increase the extent of the raising and low-
 75 ering movement of the presser element
 which is effected by the raising and lowering
 of the shaft.

2. In a pressing machine, the combination
 80 of a frame having a pressing table, an up-
 right shaft having a pressing element there-
 on supported in a forwardly extending pos-
 85 ition, and means for raising and lowering
 the shaft and simultaneously oscillating the
 shaft about a horizontal axis.

3. In a pressing machine, the combination
 90 of a frame having a pressing table, an up-
 right shaft horizontally pivoted on the
 frame at a distance above the lower end
 and carrying a pressing element to one side
 at the upper end, a treadle and mechanism
 95 operated thereby for raising and lowering
 the shaft, and means operated by the treadle
 to swing the lower end of the shaft laterally
 and thereby rock the shaft on its horizontal
 100 pivot.

4. In a pressing machine, the combination
 105 of a frame having a pressing table, a press-
 ing element pivotally mounted on the frame,
 means for supporting said pressing element,
 a toggle link means for raising the pressing
 110 element, a toggle link side shifter for the
 supporting means, and means for simulta-
 neously operating both toggles.

5. In a pressing machine, the combination
 115 of a frame having a pressing table, a press-
 ing element, an upright shaft for supporting
 the pressing element, said shaft being piv-
 otally supported on the frame, a toggle sup-
 port for the shaft and a toggle brace for
 120 shifting the shaft laterally, and means for
 125 shifting the shaft laterally, and means for

simultaneously straightening out both toggles to elevate the shaft and shift the same laterally.

6. In a pressing machine, the combination of a main frame having a pressing table thereon, an upright shaft having a laterally shifting support at the upper end, a pressing element carried by the laterally shiftable support, a toggle connection between the lower end of the shaft and frame, a lifting spring operable to elevate the shaft, and another spring exerting a side tension on the shaft and associated with the toggle connection to return the same to its normal position and shift the shaft laterally.

7. In a pressing machine, the combination of a frame having a stationary pressing table thereon, a shaft movable vertically, and also laterally at its upper end, a pressing element supported by said shaft at one side of its upper end and means for simultaneously raising or lowering and laterally shifting said shaft in opposite directions from a definite fixed position at one time to another definite fixed position and vice versa.

8. In a pressing machine, the combination of a frame having a stationary pressing table thereon, a shaft movable vertically and also laterally forwardly and backwardly at its upper end, a pressing element slidably mounted on said shaft at its upper end and means for simultaneously lowering and laterally shifting said shaft forwardly to one position or raising and laterally shifting said shaft backwardly to another position.

9. In a pressing machine, the combination of a main frame having a pressing table thereon, an upright shaft pivoted near its lower end and having a pressing element slidably mounted thereon, means for raising and lowering the shaft and means simultaneously operated thereby to cause the pressing element on the shaft to swing in an arc as it is raised and lowered.

10. In a pressing machine, the combination of a frame, a pressing table thereon, an upright standard pivotally mounted to swing forwardly and rearwardly bodily and at its upper end, a pressing element on and projecting forwardly from the standard, a treadle having operative connection with the standard for raising and lowering the same, and means operatively connected to the treadle, frame, and standard, to swing the shaft forwardly and backwardly as it is lowered and raised, as and for the purposes set forth.

11. In a pressing machine the combination of a frame having a pressing table, an upright shaft mounted to be raised and lowered and fulcrumed on a horizontal axis near its lower end and having a pressing element at one side to co-operate with the pressing table, and means for raising

the shaft and swinging it rearwardly upon its axis or for lowering and swinging the shaft forwardly on its axis.

12. In a pressing machine the combination of a frame having a pressing table, an upright shaft mounted to be raised and lowered and fulcrumed on a horizontal axis near its lower end and having a pressing element at one side to co-operate with the pressing table, and means for lowering the shaft and simultaneously swinging it forwardly, said means when released permitting said shaft to be raised and swung rearwardly.

13. In a pressing machine, the combination of a frame having a pressing table, a pressing element, an upright standard for supporting the pressing element, said standard being fulcrumed at its lower end and adapted for limited forward and rearward movement at said end, and means for oscillating the standard and pressing element carried thereby forwardly and rearwardly.

14. In a pressing machine, the combination of a frame having a pressing table, a pressing element, means for supporting the pressing element, means for raising and lowering the supporting means and pressing element carried thereby, and means associated with the last-named means for oscillating the supporting means and pressing element forwardly and rearwardly during the raising and lowering action to move the upper portion of the supporting means toward and away from the frame and to raise or lower and move the pressing element toward and away from the pressing table.

15. In a pressing machine, a frame, a pressing table thereon, an upright shaft pivotally mounted on said frame and having a forwardly and rearwardly shifting support at its upper end, a pressing element carried by the support, means operable to elevate the shaft, means acting against the last-named means to lower the shaft, and means exerting a forward tension on the lower end of the shaft to normally hold it forwardly and the upper end rearwardly, said means permitting said shaft to move forwardly when lowered.

16. In a pressing machine, the combination of a main frame having a pressing table thereon, an upright shaft pivotally mounted on said frame and having a slidably shifting support at its upper end, a pressing element carried by the support, said shaft being adapted to move forwardly and backwardly on an axis near its lower end and toward and away from the frame at its upper end to correspondingly shift the pressing element carried thereby, a treadle, means between the treadle and frame and operatively connected with said treadle to actuate the shaft, and means exerting a

forward tension on the lower end of the shaft to move it rearwardly at its upper end and to normally hold the lower end forwardly when the treadle is released.

by the support, means operable to raise and lower the shaft, an articulated joint between the lower end of the shaft and the frame, and means for exerting a forward tension on the lower end of the shaft, said shaft being mounted to oscillate forwardly and rearwardly as it is lowered and raised. 10

5 17. In a pressing machine, a frame having a pressing table thereon, an upright shaft having a laterally shifting support at the upper end, a pressing element carried

ANTON ZEMAN.
